UNITED STATES PATENT OFFICE.

HENRY L. SMITH, OF SCHENECTADY, NEW YORK, ASSIGNOR TO GENERAL ELECTRIC COMPANY, A CORPORATION OF NEW YORK.

AUTOMATIC OIL-SWITCH.

1,046,119.

Specification of Letters Patent.

Patented Dec. 3, 1912.

Application filed May 17, 1906. Serial No. 317,810.

To all whom it may concern:

Be it known that I, HENRY L. SMITH, a citizen of the United States, residing at Schenectady, county of Schenectady, State of New York, have invented certain new and useful Improvements in Automatic Oil-Switches, of which the following is a specification.

This invention relates to oil switches of the type disclosed by me in United States Patent 839,788, December 25, 1906, which discloses an oil switch opened either by hand or automatically; the automatic releasing means acting upon a catch which is released by hand when it is desired to open the switch. As a result of this arrangement it is impossible to tell from the appearance of the switch when open whether it was opened automatically or opened by hand. Furthermore the switch shown in said patent may be held closed by the operator, although there is an overload upon the circuit.

In carrying out my invention I provide between the handle of the switch and the operating mechanism by which the switch contacts are moved a normally positive collapsible connection so arranged that under ordinary conditions the handle is rigidly connected to the operating mechanism of the switch and the switch may be opened and closed by hand without altering the relation between the handle and the operating mechanism, while some suitable device preferably automatic, is provided for breaking the normally positive connection to free the handle from the operating mechanism, and thereby alter the relation between the handle and the operating mechanism. As a result of this arrangement the relation of the parts to each other is different when the switch has opened automatically from the position assumed when the switch is opened by hand, and as the handle is disconnected when there is an overload upon the circuit, the switch cannot be held closed on overload by means of the handle.

The object of the present invention is to provide a switch of simple and cheap construction, which may be opened by hand or automatically and which will indicate by the position of the parts how it was opened; which will trip free from the closing means

as soon as the contacts touch if there is an overload upon the circuit, and which cannot be held closed as long as there is an overload upon the circuit; to provide a simple and reliable stop to prevent the movable contacts from striking the bottom of the oil can; and in general to improve the construction of switches of this type as will be more specifically pointed out in the claims.

The invention will best be understood in connection with the accompanying drawings in which—

Figure 1 is a view partly in section showing the switch in the closed position; Fig. 2 is a similar view showing the position assumed when the switch is open; and Fig. 3 a view of a detail of the switch.

The switch shown in the drawings is intended to control a three-phase circuit and is mounted upon a suitable panel or support 1. A frame 2 is provided, preferably made of pressed steel, and this frame is held to the panel 1 by means of bolts 3. The frame carries a base 4 of slate, soapstone or other insulating material which is also a non-conductor of heat. Three pairs of fixed contacts 5 are carried by the base 4, being firmly held in position by means of nuts 6 engaging the upper ends of the contacts. The base 4 is not inductively affected by alternating current flowing through the contacts 5, and does not become heated, as a metallic base would. The lower ends of the fixed contacts carry contact fingers 7 supported by means of spring-blades. Bridging contacts 8 are provided by means of which the circuit is closed between each pair of fixed contacts. The bridging contacts are carried upon supporting rods 9 of wood or other similar insulating material, and the upper ends of the rods are secured to a yoke 10 which carries a plate 11. An oil can 12, preferably of metal and provided with a lining 13 of insulating material, is firmly secured to the frame 2 in engagement with the base 4.

That part of frame 2 next to panel 1 carries supporting plates 14 in the upper end of which is mounted a pin 15. A lever 16 made of two separate plates passing on each side of the plates 14, is mounted upon the pin 15. A stop 17 in the form of a bell-crank lever having stops 19 on one end thereof, is mounted upon the pin 15; the other end 18

of the bell-crank lever engages the frame 2. The lever 16 carries a connecting-pin 20 by means of which the lever is attached to the plate 11 and also has at one end a slot 21 in which a pin 22 moves. The pin 22 is carried in the end of one arm 23 of a bell-crank lever mounted upon a pin 25 which is carried in a standard 26 secured to the frame 2. The arm 23 and the lever 16 form an operating mechanism for the switch similar to that disclosed in the application above referred to.

A hand lever 27 is mounted upon the pivot 25 which forms a pivotal connection between the hand lever and the bell-crank lever. The hand lever is connected to the arm 24 of the bell-crank lever by means of a toggle composed of a link 28 pivoted to the arm 24 and a link 29 pivoted to the hand lever 27. The link 29 has a heel 30 which engages a stop pin 31 when the toggle is slightly overset. As a result of this arrangement, when the toggle is slightly overset there is a rigid but collapsible connection between the hand lever 27 and the arm 24 of the bell-crank lever; which connection, however, may be broken by breaking the toggle. The support or frame 2 is horizontal, and an upward movement of the handle 27 oversets the toggle and locks the handle firmly to the operating mechanism by means of which the contacts are lifted upward into circuit closing position. In closing the switch the operator presses the handle 27 downward, and can place his weight upon the handle if necessary to force the switch closed. A latch 32 is pivoted to the frame 2 and has a hook 33 and a handle 34. The hook 33 engages a latch-pin 35 carried by the hand lever 27 for the purpose of holding the hand lever in the position shown in Figs. 1 and 2. The hook 33 may be moved out of engagement with the latch-pin 35 by pressing upward upon the handle 34.

An overload coil 36 is secured to the frame 2 beneath the standard 26. This coil is provided with a movable core 37, and a trip-pin 38 is mounted in the frame in position to be engaged by the core 37 when the core is moved upward. The trip-pin 38 normally assumes the position shown in Fig. 1. The coil is attached to the frame by means of the supporting yoke 39 which carries a tubular member 40 provided with a slot having apertures 41, the diameter of which is considerably greater than the width of the slot. A locking plug 42 of substantially the same diameter as the apertures 41 is provided and this plug is arranged to engage a pin 43 carried by the core 37. When the plug 42 is inserted in one of the apertures 41 and is at the same time in engagement with the pin 43, the core 37 is locked in position and does not respond to the overload coil 36. A calibrating screw 44 is carried by the lower end

of the tubular member 40, and by means of this screw the position of core 37 in relation to the coil 36 may be varied, thereby varying the amount of current required to lift the core 37 and trip the switch open.

The operation is as follows:—When the switch is closed the parts are in the position shown in Fig. 1, and the toggle 28, 29 being overset forms a positive connection between the hand lever 27 and the arm 24. As a result of this connection the hand lever 27 and the bell-crank lever 23, 24 form a rigid lever which swings about the pivot 25 as a fulcrum. If it is desired to open the switch by hand, the handle 34 is moved upward, thereby moving the hook 33 out of engagement with the latch-pin 35, permitting the hand lever 27 and the bell-crank lever to swing about the pivot 25, and the switch opens. If, however, while the switch is closed an overload should occur upon the circuit, the coil 36 is energized sufficiently to attract the core 37 and bring it into engagement with the trip-pin 38. The trip-pin is raised into engagement with the lower surface of the toggle link 28, thereby breaking the toggle 28, 29, and causing the connection between the hand lever 27 and the arm 24 to be broken. The hand lever is locked in position and the switch is held closed because the tendency of the bell crank 23, 24, to move on its pivot is resisted by the overset toggle 28, 29, having one end secured to the hand lever, and when the toggle breaks the switch opens owing to the weight of the bridging contacts 8 and the rods 9 and the parts assume the position shown in Fig. 2. The lever 16 moves downward into engagement with the stops 19 on the bell-crank lever 17 and the end 18 of the bell-crank lever comes into engagement with the frame 2, thereby forming a positive lock which prevents further downward movement of the lever 16 and stops the bridging contacts 8 in position shown in dotted lines in Fig. 1. Owing to the collapse of the toggle 28, 29 the downward movement of the bridging contacts 8 is permitted without alteration in the position of the hand lever 27, which remains locked by the latch 32 in the position shown in Fig. 2. When the attendant sees the parts of the switch in the position shown in Fig. 2, he knows that the switch has been opened automatically. If it be desired to close the switch, the hand lever 27 is moved in the direction of the arrow *b* in Fig. 2, thereby straightening the toggle 28, 29, until it assumes an overset position as shown in Fig. 3. The result of this movement is to establish a positive connection between the hand lever 27 and the arm 24, and therefore when the hand lever 27 is moved in the direction of the arrow *a* in Fig. 1, the bell-crank lever 24, 23, is moved about its pivot, causing the switch elements to assume the position

shown in Fig. 1. When the switch is closed the catch 32 engages the latch-pin 35 and the switch is held closed as shown in Fig. 1.

Many changes and alterations may be made in the form in which my invention is embodied, and I therefore do not wish to be restricted to the exact structure shown, but intend to cover by the terms of the appended claims all changes and modifications 10 within the spirit and scope of my invention.

What I claim as new and desire to secure by Letters Patent of the United States, is,—

1. An electric switch comprising a movable element, a bell-crank operating lever 15 having one arm connected to said element, a pivot for said lever, an operating handle mounted on said pivot, and a locking toggle connecting said handle with the other arm of said lever.

2. An electric switch comprising a movable element, a bell-crank lever having one arm connected to said element, a pivot for said lever, an operating handle mounted on said pivot, a normally positive collapsible 25 connection between said handle and the other arm of said lever, and means for collapsing said connection.

3. An electric switch comprising a base, a pivot carried by said base, a bell-crank operating lever mounted on said pivot, an oper- 30

ating handle mounted on said pivot, a contact movable at right angles to said base, connections between one arm of said lever and said contact, a toggle connection between the other arm of the lever and the operating handle, a latch mounted on the base 35 and engaging said handle, and means for breaking said toggle connection.

4. In an oil switch, a horizontal support, an operating arm for closing said switch 40 when moved upward, an operating handle having a pivotal connection with said arm, a collapsible connection between said arm and said handle, automatically set in non-collapsed position by upward movement of 45 the handle, whereby a downward movement of said handle causes an upward movement of said arm, and means for collapsing said collapsible connection.

5. In an electric switch, a support, an operating arm, a pivot on said support for said arm, and a stop lever mounted on said pivot having one end engaging said arm and the other end engaging the support. 50

In witness whereof, I have hereunto set 55 my hand this 16th day of May, 1906.

HENRY L. SMITH.
